[57] CLAIM

The ornamental design for a stove, as shown and described.

DESCRIPTION

FIG. 1 is a perspective view of a stove showing my new design;

FIG. 2 is a front elevational view thereof;

FIG. 3 is a left side elevational view thereof;

FIG. 4 is a rear elevational view thereof;

FIG. 5 is a top plan view thereof;

FIG. 6 is a perspective view of a second embodiment thereof, wherein the only difference resides in the position and configuration of the flue port,

FIG. 7 is a rear elevational thereof; and

FIG. 8 is a top plan view thereof.

FIG.1

FIG.2

FIG.3
